BY *George W. Leland*
ATTORNEY

UNITED STATES PATENT OFFICE.

LOUIS B. HARVEY, OF STOCKTON, CALIFORNIA, ASSIGNOR TO HARVEY RIM & WHEEL COMPANY INC., OF BUFFALO, NEW YORK.

RIM CONSTRUCTION FOR DISK WHEELS.

1,376,808.

Specification of Letters Patent. Patented May 3, 1921.

Application filed March 8, 1920. Serial No. 364,162.

To all whom it may concern:

Be it known that I, LOUIS B. HARVEY, a citizen of the United States, residing at Stockton, in the county of San Joaquin, 5 State of California, have invented certain new and useful Improvements in Rim Construction for Disk Wheels; and I do declare the following to be a full, clear, and exact description of the same, reference being had 10 to the accompanying drawings, and to the characters of reference marked thereon, which form a part of this application.

This invention relates to improvements in rim structures for disk wheels, being especially intended to be used with an arrangement of disks as shown in my co-pending application for patent filed March 15th, 1919, Serial No. 282,935.

It is also particularly adapted to be used 20 with a demountable rim of the type shown in my co-pending application for patent filed March 25th, 1919, Serial No. 284,983.

The principal object of the present invention is to provide a one-piece pressed 25 steel fixed rim which will have great strength against warping out of round and in a transverse direction, and yet one which will have sufficient elasticity to enable it to contract somewhat transversely when it is 30 desired to secure the demountable rim thereto, so that the rim may be tightly cinched in place.

A further object of the invention is to produce a simple and inexpensive device, 35 and yet one which will be exceedingly effective for the purposes for which it is designed.

These objects I accomplish by means of such structure and relative arrangement of 40 parts as will fully appear by a perusal of the following specification and claims.

In the drawings similar characters of reference indicate corresponding parts in the several views.

Figure 1 is a cross section through the 45 felly.

Fig. 2 is a similar view showing a modified form of structure.

Referring now more particularly to the 50 characters of reference on the drawings, and particularly to Fig. 1 thereon, the numeral 1 denotes a fixed rim having an annular outwardly projecting plane flange 2 on the inner edge and a similarly disposed but con- 55 vexly curved flange 3 on its outer edge. This

forms the main rim member, which is thus channel shaped in cross section.

The inner flange 2 projects outwardly beyond the flange 3, and has an internally disposed V-shaped groove 4 at such point 60 adapted to receive the inner edge of an annular flange 5 of the demountable rim 6, the latter being the type shown in my co-pending application previously mentioned.

Convexly curved to conform to the contour of the flange 3 is a locking ring 7, outside said flange, which has a V-shaped groove 8 oppositely disposed to but in alignment with the groove 4 when in position.

The groove 8 is adapted to engage the 70 inner edge of the outer annular flange 9 of the rim 6.

The flange 2 receives thereagainst the inner disk 10 of the wheel, while the intermediate and outer disks 11 and 12 respectively are convexly curved at their outer peripheries and set against the flange 3 between the same and the locking ring 7.

Bolts 13 pass through the flanges 2 and 3, the disks, and the locking ring 7, so that 80 by turning up on the nuts 14, the entire structure is bound tightly together, the channel shape of the fixed rim permitting the flanges thereof to contract slightly to enable the demountable rim to be tightly cinched in 85 place therebetween.

Referring to Fig. 2, the same principle of construction is embodied in the felly, which has a fixed rim 1^a and annular flanges 2^a and 3^a, both the latter however being convexly curved.

An inner locking rim 15 is secured to the inner flange and projects outwardly beyond the same, forming a seat in conjunction with the flange 2^a for the flange 5 of the rim 6. 95

A locking ring 7^a of the same form as the ring 7 is employed on the outside of the outer flange 3^a to hold the outer flange 9 of the rim.

The disk 10 passes between the inner 100 flange and locking rings, while the other disks 11 and 12 terminate between the outer flange and locking ring, as in the first described construction. Bolts 13^a and nuts 14^a have the same functions in this latter 105 construction as in the former.

The advantages of this form of construction over the former are that the fixed rim member is more easily pressed out, and also the inner locking ring forms a more secure 110

binding or clamp for the inner disk of the wheel.

From the foregoing description it will be readily seen that I have produced such a 5 device as substantially fulfills the object of the invention as set forth herein.

While this specification sets forth in detail the present and preferred construction of the device still in practice such deviations from such detail may be resorted to as 10 do not form a departure from the spirit of the invention, as defined by the appended claims.

Having thus described my invention what 15 I claim as new and useful and desire to secure by Letters Patent is:—

1. A rim structure for wheels comprising a fixed rim, annular flanges projecting outwardly from the inner and outer edges thereof 20 of and formed integral therewith, an extension on the inner flange projecting outwardly beyond the outer flange and arranged to seat one edge of a demountable

rim thereagainst, a locking ring outside the outer flange extending outwardly therebeyond and adapted to bear against the outer edge of the rim, and bolts through the flanges of the fixed rim and the locking ring, whereby said flanges may be drawn toward each other to cause the rim flange and locking 30 ring to pinch and bind the rim in place.

2. A rim structure for demountable rims comprising a channel-shaped fixed rim, having outwardly extending flanges, the inner one of such flanges being of greater diameter than the outer flange and arranged to seat one edge of a demountable rim adjacent the outer edge thereof, a locking ring adapted to engage the other edge of the demountable rim positioned outside the outer flange, 40 and a common means for holding the locking ring in position and for pinching the flanges together to cause the rim flange and locking ring to clamp the demountable rim in place.

In testimony whereof I affix my signature. 45
LOUIS B. HARVEY.
